UNITED STATES PATENT OFFICE.

JULIUS C. SULLIVAN, OF WARREN, PENNSYLVANIA.

SAFETY VALVE.

Application filed April 11, 1921. Serial No. 460,222.

To all whom it may concern:

Be it known that I, JULIUS C. SULLIVAN, a citizen of the United States, residing at Warren, county of Warren, and State of Pennsylvania, have invented certain new and useful Improvements in a Safety Valve, of which the following is a specification:

My invention relates to safety valves and particularly to safety valves especially designed for use in conjunction with tank cars, steamship tankers, or any such containers for quantities of volatile liquid.

Storage and shipping tanks for volatile liquids are frequently subjected to high internal pressure due to the volatilization of the liquid under varying atmospheric conditions, and it is essential that this pressure be relieved before reaching a sufficient degree to rupture or burst the tank. Also, when such tanks, particularly tank cars, are involved in accidents, the volatilization of the liquid is frequently rapid with a consequent rapid rise in the pressure within the tank. It is essential at such times that the gases be permitted to escape and at the same time flames be prevented from entering the tank, should the gases become ignited. Also, gases escaping from such cars are frequently ignited when the cars are adjacent a locomotive as frequently happens in switching cars in the railroad yards and means should be provided to prevent the flames from entering the tank.

The object of my invention is to provide a safety valve with means which will permit escape of the gases after they have reached a predetermined pressure. A further and particular object of my invention is to provide a device of this character, which will permit of the escaping of the gases only after the same shall have reached a predetermined popping pressure, to the end that a continuous or prolonged discharge of small quantities of gas shall be avoided. A further object of my invention is to provide a device as mentioned in which the valve will quickly and securely close as soon as the pressure is reduced below the predetermined popping pressure. A further object of my invention is to provide means for quickly extinguishing any flames as the valve is closed. A further object of my invention is to provide a device of the character mentioned which may be readily adjusted to operate under the desired pressure. A further object of my invention is to provide a device of the char-

acter under consideration of such construction that the escaping gases, under pressure, shall be directed to a central vertical axis above the valve casing. A further object of my invention is to provide a safety valve as mentioned of such construction that the various parts and mechanisms shall present a minimum amount of obstruction to the escaping gases. Further objects of my invention are to provide a device as mentioned which will be of simple construction, which will not readily get out of order and in which the various elements may be readily adjusted, repaired or replaced. Other objects will appear hereinafter.

With these objects in view my invention consists generally in a valve casing and main valve in combination with means for locking said valve in closed position until the vapors have reached a predetermined pressure. My invention further consists in a device as mentioned in combination with means for initially actuating the locking mechanism to release the valve when the gases have reached a predetermined pressure. My invention further consists in a device as mentioned in which the locking means serves to quickly close and lock the valve as soon as the vapor pressure is reduced below the predetermined popping pressure. My invention further consists in a safety valve comprising a casing and valve in combination with means for automatically extinguishing the flames should the escaping vapors become ignited. More specifically, said flame extinguishing means comprises a shutter or shutters adapted to automatically close said casing as the valve closes to exclude air from adjacent the latter. My invention consists in various details of construction and arrangements of parts, all as will be fully described hereinafter and particularly pointed out in the claims.

My invention will be more readily understood by reference to the accompanying drawings forming a part of this specification and in which—

Fig. 1 is a side elevation, partially in section, of a safety valve embodying my invention, parts being shown in elevation,

Fig. 2 is a top plan view of the device,

Fig. 3 is a bottom plan view,

Fig. 4 is a vertical section on the line 4—4 of Fig. 1, and,

Fig. 5 is a transverse section on substantially the line 5—5 of Fig. 4.

Referring now to the drawings, 1 indicates the housing which comprises a lower cylindrical intake chamber portion 2 and an upper discharge portion 3. The exterior 5 of the housing, intermediate the portions 1 and 2, is threaded as at 4 for securing the device in position in the usual manner, as illustrated in Fig. 4. The upper portion 3 is provided with means 5 for engagement 10 with a wrench, for securing the device in position, or removing the same. The portion 2 is provided with inlet apertures 6 in its walls to facilitate the free passage of gases.

15 Between the chambers 2 and 3 is an annular valve seat 7. This is preferably removable so that the same may be readily repaired or replaced in case of wear. 8 indicates the valve which normally rests on 20 the seat 7. This is provided with a depending hollow stem 9 which constitutes a timing valve barrel as will appear hereinafter. The valve 8 and valve seat 7 are preferably made of non-corrosive metal. Supported 25 within the chamber 2 by arms 10 is a sleeve 11 which serves as a guide for the barrel 9. 12 indicates a bushing threaded into the upper end of the barrel 9, and 13 indicates a lock nut for securing the same in adjusted 30 position. Extending through the bushing 12 and barrel 9 is a valve stem 14 terminating at its lower end in a squared head 15. The upper end of the stem 14 is threaded, and threaded thereon is a sleeve 16 held in 35 adjusted position by a lock nut 17. The sleeve 16 carries a laterally extending flange 18 at its upper end for a purpose herein-after described.

40 From the construction so far described, it is obvious that the valve 8 is subjected to the pressure within the tank or reservoir, and as one of the primary objects of my invention is to prevent the valve from permitting escape of gases until the pressure 45 has reached a predetermined "popping pressure", means must be provided for normally locking the valve on its seat. To this end, I provide a transverse member 19 at the bottom of the chamber 2 which rests 50 upon the head 15 and normally held in depressed position by a pair of pivoted arms 20. The arms 20 are pivoted between the arms 10, as on pins 21, and carry at their lower ends anti-friction rollers 22 which engage 55 the member 19. These arms are normally pressed inwardly by springs 23 having seats 24 in the walls of the housings and seats 25 in the arms, as illustrated clearly in Fig. 4. The member 19 is vertically movable with the valve 8 and the ends of said member and the housing are provided with co-operating guiding means. For this purpose, I provide the housing with vertically disposed ribs 26 and notch the ends of the 60 member 19, as at 27, to receive them. The

lower face of the member 19 is provided with a socket 28 to receive the head 15 of the valve stem and to prevent the same from turning. The upper face of the member 19 is formed with a flat centrally disposed portion 29 upon which the rollers 22 normally rest, and outwardly and downwardly curved portions 30 which constitute cam faces for co-operation with the rollers 22.

As the arms 20 securely lock the valve in 75 closed position, means must be provided for tripping or initially moving the locking mechanism above described, when the pressure has reached the predetermined point, in order to permit the valve to open. To 80 this end, a timing piston is arranged within the barrel 9 and equipped with means for moving the rollers 22 from the flat face or shoulder 29 of the member 19 on to the cam faces 30. 31 indicates a sleeve freely slidable on the stem 14 and terminating in a conical lower end 32 which rests on the face 29 of the member 19 and which is normally engaged by the rollers 22. On the upper end of the sleeve 31 is formed the timing piston which comprises a cup washer 33 and a packing expander ring 34, threaded upon the upper end of 31. Interposed between the ring 34 and the bushing 12 is a spring 35. 31' indicates a packing ring secured in 85 a recess in the bottom of the portion 32 and surrounding the stem 14 to prevent the gases from following up the valve stem into the barrel 9.

90 The operation of the portions of the device so far described is as follows: Normally the parts are in the positions indicated in full lines in Fig. 4 of the drawing. It will be noted that at this time the rollers 22 rest upon the flat face or shoulder 29 of the member 19 which prevents upward movement of the member 19 and therefore of the valve 8. When predetermined popping pressure has been reached the pressure of the gases on the timing piston 33-34 forces 95 said valve upwardly against the tension of the spring 35. The upward movement of the timing piston raises the conical portion 32 of the member 31, thereby forcing the rollers 22 off of the shoulder 29 and on 100 to the cam faces 30. The pressure on the under face of the valve 8 then raises the valve, and the valve in raising, lifts the member 19, the cam faces 30 thereof forcing the arms 22 outwardly into the position 105 shown in dotted lines in Fig. 4. These arms, and the member 19, obviously limit the upward movement of the valve 8. It is obvious that the popping pressure may be regulated by adjustment of the bushing 110 12, thereby more or less compressing the spring 35. As soon as the pressure is reduced below "popping pressure," the springs 23 force the arms 20 inwardly, thereby depressing the member 19 and seat- 115 120 125 130

ing the valve 8. The rollers 22, riding upon the shoulder 29, again lock the valve against operation until the popping pressure is again reached.

5 When gases escaping from an orifice are ignited, the distance of the flame from the orifice is dependent upon the force of the gases at the orifice; that is, if the gases are escaping slowly and without much pressure, 10 they burn close to the orifice, but if the gases are being ejected under great pressure, consequently with great velocity, they burn only at a distance from the orifice where the velocity becomes lessened. It is obvious 15 therefore, that by permitting the gases to escape only at considerable pressure, and avoiding leakage of gas in small quantities, the likelihood of the gases adjacent the valve becoming ignited is reduced to a minimum. 20 To maintain the escaping gases concentrated and at the greatest velocity, I shape the portion 3 so that the escaping gases shall be directed to a central vertical axis above the valve casing. To this end, the walls 25 of the portion 3 converge inwardly as shown clearly in the several figures of the drawing, thereby serving as a nozzle for concentrating escaping gases into a vertical column under high pressure. However, when the 30 valve closes, the flame from ignited gases, may follow the gas to the valve, and one of the objects of my invention is to equip the device with means for extinguishing any such flames adjacent the valve. To this 35 end, the discharge opening or mouth of the portion 3 is provided with means for cutting off air from the valve, and this means preferably comprises a hinged or pivoted closure. As illustrated in the drawing, 40 I have provided the device with a pair of closure members pivoted on substantially parallel axes. 36 indicate the closures which are pivotally mounted upon trunnions 37 supported in upwardly extending lugs 38 on the housing 1. Each 45 of the closures is provided with a depending member 39 which is notched to receive the flange 18. It is obvious that the member 16 moves upwardly with the valve 8, and 50 with the construction shown, opens closures 36, as shown in dotted lines lines in Fig. 4. It will be noted that when the closures 36 are opened, they are inclined upwardly and inwardly, so as to assist the tapered end 55 of the portion 3 in directing the gases centrally above the casing. As the valve 8 drops upon its seat, the flange 18, engaging the members 39, quickly closes the mouth of the housing by means of the closures 36, 60 thus extinguishing any flame that might have followed the gases to the valve as the latter closed.

It will thus be seen that the device above described effectually prevents the contents of 65 the container from being ignited from the

discharge of the gases through the valve. First, the gases are only discharged when under considerable pressure, so that should they become ignited the flame will be maintained at a safe distance from the valve, and 70 second, should the flame follow the gas as the valve is closed, the closure members 36 will quickly extinguish the flame.

While I have described my invention for use in conjunction with tanks or reservoirs 75 for volatile liquids, it is obvious that the same may be effectually used as a safety valve for steam boilers, compressed air tanks, or in any situation where it is essential to provide a safety valve for relieving 80 internal pressure after a predetermined pressure has been reached.

I claim:—

1. A device of the class described, comprising a housing, a valve therein, a cam surface and shoulder carried by said valve, a pivoted arm on said housing, a roller on said arm normally engaging said shoulder to lock the valve in closed position, and pressure actuated means adapted to move said roller 90 from said shoulder to said cam surface to unlock the valve, substantially as described.

2. A device as set forth in claim 1 in combination with a spring forcing said arm towards said shoulder as and for the purpose 95 specified.

3. A device of the class described comprising a housing, a main valve therein, a timing piston barrel carried by said main valve, a timing piston therein, a shoulder and cam 100 surface movable with said piston, a pivoted arm provided with a roller normally engaging said shoulder for locking the main valve in closed position, and means carried by said timing piston for moving said roller from 105 said shoulder to said cam surface, substantially as described.

4. A device as set forth in claim 3, further characterized by a bushing threaded into said timing piston barrel and a spring interposed between said bushing and said timing piston, substantially as described.

5. In a device of the class described, a housing, a main valve therein, a timing piston barrel carried by said main valve, a 115 stem extending through said barrel, a member carried by said stem and provided with a shoulder and cam face, a pivoted arm on the housing provided with a roller normally engaging said shoulder, a sleeve slidable on said stem, a timing piston on one end of said sleeve and within said barrel, and means on the opposite end of said sleeve for moving said roller from said shoulder to said cam surface, substantially as described.

6. A device as set forth in claim 5 in combination with a spring forcing said arm and roller towards said shoulder, substantially as described.

7. A device as set forth in claim 5 in com-

130

- bination with a bushing threaded into said barrel and a spring interposed between said bushing and the timing piston, substantially as described.
- 5 8. A device of the class described, comprising a housing, a valve seat dividing said housing into inlet and discharge portions a main valve normally resting on said seat, a timing piston barrel depending from said 10 valve, a stem extending through said barrel and projecting below the same, a transverse member carried by the lower end of said stem and provided with a shoulder and cam surfaces, a pair of arms pivotally mounted 15 within said housing, and provided with rollers engaging said shoulder, a timing piston
- within said barrel, means carried by the timing piston for moving said rollers from said shoulder to said cam surfaces, springs forcing said arms towards said shoulders, a 20 bushing threaded into said barrel and a spring interposed between said bushing and said timing piston, substantially as described.

In testimony whereof I have signed my 25 name to this specification in the presence of two subscribing witnesses.
